UNITED STATES PATENT OFFICE.

CLARENCE A. MYERS, FREDERICK W. HAAS, JR., AND ALVAH A. MYERS, OF CHICAGO,
ILLINOIS.

IGNITING MECHANISM FOR INTERNAL-COMBUSTION ENGINES.

No. 890,247.

Specification of Letters Patent.

Patented June 9, 1908

Application filed March 7, 1908. Serial No. 419,794.

To all whom it may concern:

Be it known that we, CLARENCE A. MYERS, FREDERICK W. HAAS, Jr., and ALVAH A. MYERS, citizens of the United States, residing at Chicago, in the county of Cook, State of Illinois, have invented certain new and useful Improvements in Igniting Mechanism for Internal-Combustion Engines; and we do hereby declare the following to be a full, clear, and exact description of the same, reference being had to the accompanying drawings, forming a part of this specification, and to the figures and letters of reference marked thereon.

This invention relates to improvements in mechanism for igniting the explosive charge of internal combustion engines, the invention being more especially applicable to engines wherein the ignition is effected by an electric spark or arc drawn between contacts or electrodes as they are separated, and the objects of the invention are to provide a mechanism adapted for handling a low tension current of electricity which may be readily substituted for the mechanism of a high tension system without change in the arrangement or construction of the engine itself; thus the electrodes of the present mechanism are mounted in a plug which is adapted to be substituted for the usual high tension or jump spark plug.

The invention consists in certain novel details of construction and combination and arrangement of parts all as will be now described and pointed out particularly in the appended claims.

In the accompanying drawings: Figure 1 is a sectional elevation showing a sparking apparatus embodying the present improvements. Fig. 2 is an end view of the spark plug showing the preferred form of contacts or electrodes, and Fig. 3 is a section on the line 3—3 of Fig. 1.

Like letters of reference in the several figures indicate the same parts.

In said drawings the letter M indicates the head or other wall of the cylinder of an internal combustion engine having the usual spark plug aperture m therein. Screwing into this aperture m is a plug body A of any suitable metal or other material having sufficient strength and adapted to carry the electrodes and their supporting shafts. Both electrodes in the present device are movable, one being

preferred arrangement the oscillatory electrode B is mounted on a shaft B' journaled in the plug or body A and adapted to be held in its normal position with a yielding pressure by a spring C coiled about the outer end of the shaft B', connected at one end to said shaft and at the opposite end to the plug or other fixed part. The rotary electrode D is mounted on a shaft D', but this shaft D' is journaled in a sleeve d mounted in, but insulated from, the body of the plug by an insulating bushing d', whereby the electrode and its shaft may constitute one terminal of a circuit, the other terminal of which is formed by the electrode B.

In order to inclose the outer end of the bearings through which the electrode shafts pass, a cap E is provided for the plug, such cap being held in place by a screw or screws F, but insulated from the body A of the plug by a gasket or packing ring f, the latter also serving to prevent any possible escape of pressure or blowing through the plug itself. The shaft D' is extended through the upper wall of the cap E, and, for convenience, is provided with a gland or suitable packing 80 box E' of well understood construction.

The mechanism for rotating the shaft D' and electrode D embodies a means whereby the timing of the movement of the electrode with relation to the power shaft may be varied in order to advance or retard the inauguration of the period of ignition, and as a convenient and novel means for accomplishing this end which will permit the parts to be readily separated and again restored to their proper relations without requiring special skill, the shaft D' is provided at its upper end with a bevel gear H meshing in a gear I on a sparkler shaft J, which latter may be adapted for operating as many 95 sparking contacts as there are cylinders in the engine to which the apparatus is applied. The shaft J carries a sliding sleeve K held against independent rotation thereon, as by a spline or feather j, and upon or in its outerface 100 there is formed a spiral k, said spiral constituting the driving connection between the sleeve K and a driving gear N, deriving its motion from the crank shaft through any suitable intermediate gearing, such, for instance, as the shaft and bevel pinion L. The sleeve K is further provided with a means such as the groove or collar O, whereby it

- may be shifted longitudinally of the shaft J without disturbing the driving connections, but such shifting of the sleeve necessarily advances or retards the spark shaft J with 5 relation to the driving mechanism, whereby it is a matter of very simple adjustment to advance or retard the spark in accordance with the requirements for running the engine at any particular speed.
- 10 To facilitate the adjustment of the spark plug in proper relation to the other working parts of the device and cylinder, gages G and G' are mounted on the body A of the plug and cylinder M respectively.
- 15 From an inspection of Fig. 2 it will be seen that the electrode or contact B is in the form of a curved arm, the end b of which projects in proximity to, but not in contact with, the body of the terminal of the electrode D and the electrode D' is provided with a rounded projection D² adapted to make a long wiping contact with the inner side of the arm B and to pass off or away from the end of said arm during the forward 20 rotation of the shaft D'. It will also be noted that the end b of the arm is rounded sufficiently to permit reverse rotation of the electrode D without danger of catching against the projection D², and hence no 25 damage can be done should the engine reverse or the crank shaft be reversed through 30 design or accident.
- It will be noted that with a sparking apparatus such as described the electrodes are 35 not liable to become fouled by accumulations thereon, perfect contact is insured at all times between the electrodes at one point during the rotation of the electrode D, the plug is interchangeable with plugs of ordinary 40 construction, and there is no danger of the spark being killed by oil in the cylinder or which may work in between the circuit connections. The circuit is formed through the shaft D' and shaft J, the latter 45 being also insulated from the body of the engine or ground. This arrangement permits of the shaft J being utilized to supply current to all the spark plugs in a multiple cylinder engine.
- 50 Having thus described the invention, what

is claimed as new and desired to be secured by Letters-Patent is:

1. In a sparking apparatus for internal combustion engines, the combination with a plug having a threaded body, of electrode shafts journaled in said body to have oscillatory and rotary movements, rotary and oscillatory electrodes carried by said shafts, a driving connection for rotating one of said shafts, a spring carried by the outer end of the oscillatory shaft for holding the electrode advanced with a yielding pressure, a cap inclosing the outer end of the plug, and a packing gland through which the rotary shaft projects from the cap, substantially as described. 60

2. In a sparking apparatus for internal combustion engines, the combination with a plug body having a threaded projection and electrode shafts journaled in said body and having electrodes at their inner ends, of an insulating bushing for one of said shafts, a spring mounted on the outer end of the other of said shafts, a cap inclosing the outer end of said last mentioned shaft and having a gland through which the other shaft projects from the cap, and a rotating driving connection for said last mentioned shaft. 75

3. In a sparking apparatus for internal combustion engines, the combination with a plug body having a threaded projection adapted to extend through the cylinder wall, and shafts journaled in said plug body and having electrodes on their inner ends, of an insulating bushing for one of said shafts, a spring carried by the outer end of the other of said shafts for holding its electrode advanced with a yielding pressure, a cap inclosing the outer end of said last mentioned shaft, a gland through which the other shaft projects, an insulating gasket between said cap and plug, and a rotating driving connection for the last mentioned shaft; substantially as described. 80 85 90
